(57) **CLAIM**

The ornamental design for a docking station for telephone and flat computer, as shown and described.

DESCRIPTION

FIG. 1 is front perspective view of our docking station for telephone and flat computer which can hold a handset and a smart phone, tablet computer or similar flat electronic device; FIG. 2 is a top view thereof; FIG. 3 is a bottom view thereof; FIG. 4 is a front view thereof; FIG. 5 is a rear view thereof;

FIG. 6 is a right side view thereof; and, FIG. 7 is a left side view thereof.

The broken lines in the drawings depict parts of the docking station for telephone and flat computer that form no part of the claimed design.

1 Claim, 7 Drawing Sheets
